BASE CHANNEL-PANEL FOOTING STRUCTURE
Jon B. Dunnington, Mercer Island, Wash., assignor to
Butler Manufacturing Company, a corporation of
Missouri

Filed Aug. 3, 1961, Ser. No. 129,042
4 Claims. (Cl. 50—186)

This invention relates to footing mountings for panels and refers more particularly to a base channel-post footing cooperating construction for wall panels of a building.

This application is a continuation-in-part of my application Serial No. 49,265, filed August 12, 1960, for "Joint Assembly for Wall Panels," now Patent No. 3,102,612.

A principal area of difficulty in any prefabricated building having outside walls made up of a plurality of panels placed in side by side coplanar relationship is the obtaining of a satisfactory panel footing-sill connection. Such a panel footing-sill connection must be strong and rugged to provide long time support under load. It must be simple and easy to install and to engage the parts thereof. The members making up the footing preferably are cheap and relatively easy to mass produce in quantity, yet accurately formed to provide precise panel aligning engagement. It is very desirable to provide members which will provide very precise vertical, lateral and in-out alignment of the panels supported thereby. Means preferably should be provided which will tend to reduce and control any tendency to forward or rearward leaning or other movement of the panels supported thereby. It would also be preferable if the panel array could first be assembled in horizontal position and then moved upwardly into a vertical position and simultaneously into engagement with the panel foot support. Any means locking the parts of the footing assembly together should be readily accessible for removal or repair of any of the panel footing members or the panels themselves. such engaging means for the panel footing parts additionally preferably are protected against injury or damage whereby to prevent inadvertent locking of the panels to the footing. Finally, the elements of the assembly should fit very precisely and closely together whereby to provide precise alignment of the panels.

The objects of the invention are to achieve the above-listed goals and desirable features of a panel footing assembly.

Other and further objects of the invention will appear in the course of the following description.

In the drawings, which form a part of the instant specification and are to be read in conjunction therewith, an embodiment of the invention is shown and, in the various views, like numerals are employed to indicate like parts.

FIG. 1 is a perspective view from above of the subject panel footing engagement with portions of the panel assemblies themselves shown to better illustrate the cooperative footing construction, parts cut away in section to better illustrate the various elements.

FIG. 2 is a cross-sectional view through the inventive panel footing assembly, the unit shown in full lines in assembled position and in dotted lines in preassembly position.

Referring to the drawings, in FIGS. 1 and 2 there are shown portions of typical panel type wall members in which the joints between adjacent panels are formed in the manner disclosed in my application Serial No. 49,265, supra. The individual panel members are typically of rectangular shape. Such panel is generally constructed of a central core 10a which may be of a conventional honeycomb construction of suitable rigid thermal insulat-

ing material, faced on opposite sides with sheet metal skins 10b and 10c, or other conventional facing material. The edges of each panel have secured thereto and running lengthwise thereof a frame element in the form of an outwardly opened channel, the lower frame element being seen in FIGS. 1 and 2 and one side frame of each panel element being seen also in FIG. 1. It should be understood that the said frame elements form an integral part of the panel, being connected thereto in any suitable fashion.

The panels are mounted in coplanar relationship in a base channel set in and bolted to the foundation of the building. The lower frame element of each panel seats therein in assembled position. The upper end of the panel is received in an upper retainer structure (not shown) which forms a part of the structural framework of the building. Bolts may be employed to secure the panels in place. The particular panels shown and described herein have been selected solely for the purpose of illustrating the invention and consequently the invention hereafter to be set forth is not to be construed as limited to application to the illustrated panels alone.

The building foundation is generally designated 20 and has a trough or channel formed in the upper front edge thereof having a rear or inner wall 21 and a lower wall 22. In describing parts of the assembly the spatial orientation employed will be the full line assembled portions of FIGS. 1 and 2. A base channel having a rear or inner vertical wall 23, a horizontal bottom wall 24, a short upwardly extending front or outer flange 25 and a horizontal platform flange 26 attached to the free end of the latter is bolted by a plurality of bolts 27 and nut 28 to the said foundation. The footing extrusion, which is the circumferential edge boundary of the panel element as seen in FIG. 1, comprises a vertical rear or inner wall 29 having a horizontal base flange 30 continuously fixed thereto, a top wall 31 horizontal in assembled orientation, and a front or outer face or leg 32 vertical in orientation, the latter having a horizontal footing flange 33 analogous to flange 30 fixed to the lower free end thereof. Thus, this member, in cross section as seen in FIG. 2, looks like two erect symmetrical L-shaped members, connected at the top of the L-legs by a horizontal member 31. The width of the front horizontal flange 33 or L-base leg is preferably equal to or slightly greater than the height of front flange 25 of the base channel for reasons to be described. Legs 29 and 32 place wall 31 in line with the top of wall 23.

As previously mentioned, the panel construction proper comprises front and rear facing sheets 10b and 10c spaced by filler material 10a. The panel seal extrusion receiving the vertical facing may comprise a pair of facing U members generally designated 34 and 35 spaced slightly above a base flange 36 by strips 37 and 38. A downwardly facing front flange 39 overlies the front face 32 of the panel footing extrusion. Members 31 and 36 of the panel support extrusion and the panel footing extrusion may be bolted in face-to-face relationship as shown at 40. As previously mentioned, the detailed structure of the panel itself or its parts is not critical to the invention. The panel footing extrusion illustrated, however, is a preferred structured form and important part of the footing assembly, as is the base channel.

Openings 41 are threaded at regular intervals through the front flange 25 of the base channel to receive threaded screws or bolts 42.

In assembly of the panel, after base channel 23, etc. is bolted to the foundation, the panel base seal extrusion 36, etc. is bolted to the panel footing extrusion 31, etc. The lower ends of the panel front and rear sheets 10b and 10c are then fitted into the U-members 34 and 35 to receive same and secured therein by any suit-

able conventional means such as screws, brazing, fasteners, etc. This assembly, then, may be positioned in that alignment shown in dotted lines in FIG. 2, namely, in horizontal relationship with the front L-leg (32 and 33) of the footing extrusion overlying the front flanges 26 and 25 of the base channel. The panel assembly may then be moved in a 90° arc from the dotted line showing of FIG. 2, counterclockwise in the view, to the full line position of the same view. The L-leg base 30 prevents the rear leg 29 of the footing extrusion from catching or sticking on the foundation or rear wall 23 of the base channel. It also provides a solid seat in the assembled position for the rear panel face. Once in the assembled position of FIG. 2, the screws 42 may be screwed in from the dotted line to the full line position of FIG. 2 whereby to force the rear wall 29 of the footing extrusion against the rear wall 23 of the base channel whereby to provide a tight fit therebetween.

A plurality of weep holes 43 may be provided in the base channel to drain same prior to wall unit erection. The front L-leg base 33 preferably does not block same whereby to provide continuous drainage thereafter.

Screws 42 may be backed off at any desired time to remove any individual panel or part for replacement or repair of any part of the footing or panel structure itself.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having thus described my invention, I claim:

1. In a building structure, a foundation having a recess along one edge, a base channel anchored within said recess, said base channel having a vertical inner wall and a horizontal lower wall, said inner and lower channel walls contacting said foundation walls in said recess, said base channel including a vertical outer wall of lesser height than said inner wall, a horizontal platform flange connected to the upper edge of the vertical outer wall and extending outwardly therefrom, said outer wall being connected to said lower wall and extending normal thereto, and a wall panel having a footing member attached thereto, said footing member having a horizontal top wall with a vertical inner wall and a vertical outer

wall attached to the inner and outer edges of said top wall and extending downwardly normal thereto, horizontal flange feet fixed to the free edges of said vertical walls and extending normal thereto in the same direction, said panel footing member fitting in said base channel member with the horizontal top wall thereof substantially in line with the upper edge of the channel inner wall and with the inner wall and flange foot of the outer wall substantially abutting the opposing faces of the channel inner and outer walls, and removable means locking said footing member within said base channel member whereby said locking member may be removed and said wall panel and base channel member may be pivoted outwardly to remove said panel from its erected position, the extremity of the outermost horizontal flange foot pivoting about the intersection of the horizontal lower wall and the vertical outer wall of said base channel.

2. The building structure of claim 1 wherein said wall panel includes a panel base member overlying said horizontal top wall of said panel footing member in flush abutment therewith and removably fixed thereto, said panel base member having a vertical, downwardly extending front flange overlying the outer wall of said panel footing member.

3. The building structure of claim 1 wherein the width of the flange foot on the panel footing member outer wall is substantially equal to the height of the base channel outer wall.

4. The building structure of claim 1 further including weep holes in the base channel outer wall.
